UNITED STATES PATENT OFFICE.

ICHIRO ISHIKAWA, OF TOKYO, JAPAN.

MACHINE FOR MAKING BLEACHING-POWDER.

Specification of Letters Patent.

Patented Oct. 10, 1916.

1,200,499.

Application filed January 8, 1916. Serial No. 70,941.

To all whom it may concern:

Be it known that I, ICHIRO ISHIKAWA, a subject of the Emperor of Japan, and residing at Nishigahara, Takinogawa, Tokyo, Japan, have made a certain new and useful Invention in Machines for Making Bleaching-Powder, of which the following is a specification.

This invention relates to machines for making bleaching powder.

The object of the invention is to provide a machine for making bleaching powder which is simple in structure and efficient in operation wherein the feed of lime into the machine is controlled by the operation of the machine itself, and wherein the lime is automatically sifted at the outlet from the machine.

A further object of the invention is to prevent the machine from failing due to the accumulation of the lime within the cylinders.

A further object of the invention is to provide a chain drive for the cylinder agitators of less strength than the internal moving parts, thereby securing an external break in parts in case of failure of the machine.

Further objects of the invention will appear more fully hereinafter.

The invention consists substantially in the construction, combination, location and relative arrangement of parts, all as will be more fully hereinafter set forth, as shown in the accompanying drawing, and finally pointed out in the appended claims.

Referring to the drawings, Figure 1 is a view in front elevation of a machine embodying my invention. Fig. 2 is a view taken on the line 2—2, Fig. 1 and looking in the direction of the arrows. Fig. 3 is an enlarged view of a portion of a pair of bleaching powder chambers embodying my invention, said view being in section taken on line 3—3, Fig. 4, and looking in the direction of the arrows. Fig. 4 is a view in section taken on the line 4—4, Fig. 3, looking in the direction of the arrows. Fig. 5 is a broken enlarged view in side elevation showing a modified form of powder chamber, embodying my invention. Fig. 6 is an enlarged broken view in front elevation of the powder feeding portion of the machine partly in section. Fig. 7 is a view in elevation, partly broken, and partly sectional, showing the gas exhaust employed in accordance with my invention. Fig. 8 is a

sectional view of the same, taken on the line 8—8, Fig. 7, and looking in the direction of the arrows. Fig. 9 is a sectional view taken on line 9—9, Fig. 6, and looking in the direction of the arrows. Fig. 10 is a view in section of a powder chamber. Fig. 11 is an end view, in section, of the same. Fig. 12 is a top plan view of a powder chamber. Fig. 13 is an end view of the same.

The same part is designated by the same reference numeral wherever it occurs throughout the several views.

In the manufacture of bleaching powder, the most practical and successful machine that has been constructed and employed in the art is known as the Hasenclever machine, which consists of several superimposed tubes or powder chambers, of which any desired number can be employed in a set. Each of these tubes is provided with an agitator therein consisting of a shaft having secured thereto vanes or other suitable agitators, the shafts being rotated by a gear wheel at the end thereof outside of the tube, which gear wheel meshes with a similar gear wheel of the tubes immediately above and below. The lime is charged through a hopper into the topmost tube, and passes from tube to tube, after traversing the length of each tube due to the action of the agitator. The chlorine gas is admitted into the bottom tube, and, by suction, is drawn from tube to tube, and acts upon the lime it meets to form the bleaching powder. The gas is discharged from the topmost tube into the atmosphere and the powder from the bottom tube into any suitable receptacle. It is then carried away, and sifted and the commercial form of bleaching powder is thus secured. As hereinbefore stated, this is the usual form and operation of the Hasenclever apparatus which has proven to be commercially successful. It has been found, however, that many disadvantages have been encountered in the practical operation of the machine. In the first place, where concentrated chlorin gas was employed, the action of the gas on the lime causes the same to become greatly heated, and consequently the product is decomposed, and comes out mostly as calcium chlorid. Where weaker gas is employed the product is in most cases too weak for commercial use. It was found necessary, therefore, to run the machine intermittently with the concentrated gas,

thereby greatly reducing the efficiency of the machine, and the output thereof. Further, it was found that the lime tended to accumulate within the cylinders or tubes, and, the 5 agitators being driven by meshed gear wheels, the agitators or the shaft on which they were mounted, or the gear wheels themselves would frequently break, putting the machine out of commission. Further, at the 10 point of communication between tubes of each pair, the lime or products has a great tendency to accumulate, with the consequence that the gas, going in the opposite direction, fails to properly act upon the same, thereby greatly affecting the quality 15 of the product.

To overcome these and many other disadvantages of this type of machine, my present application is especially directed.

20 In carrying out my invention I employ the usual tubes or powder chambers 1, each communicating with the one immediately above and immediately below it through the passages 2, all of the tubes or chambers being 25 suitably supported in a frame 3, and arranged one above the other, as shown. In the form shown, I employ six such tubes, each of which being supplied with the usual agitator shaft 4, upon which are mounted 30 the vanes or blades 5, which, upon the rotation of the shaft affords the agitation of the lime which is fed into the topmost tube through a suitable hopper 6, and which drops from the bottom tube into any suitable 35 receptacle 7. The chlorin gas is fed into the bottom cylinders through a port 8, or it may be fed into any number of cylinders, as shown, through such a port, and is forced or sucked through the tubes and out 40 through a suitable exhaust 9. Each of the shafts 4 is provided with a sprocket wheel 10, and two of said shafts, preferably the second from the top and the bottom one, have secured thereto a second sprocket wheel 45 11, as shown. A suitable chain 12 operates between sprocket wheels of the top and third from the top tubes, and over the sprocket wheel of the second from the top tube. Likewise, a similar chain 13 operates be- 50 tween the sprocket wheels of the bottom and third from the bottom tubes, and over the sprocket wheel of the second from the bottom tube, all as clearly shown. Suitably journaled in the frame 3, is a worm shaft 14, 55 which upon rotation actuates a wheel 15, which is carried by a shaft 16, also suitably journaled in the frame 4. Mounted on the shaft 16, to rotate therewith are two sprocket wheels 17 which are suitably con- 60 nected, such as by chains 18, with the respective wheels 11. Thus it will be seen that when the shaft 14 is rotated, the agita- 65 tor shaft of each individual tube will in turn be rotated. The worm shaft 14 may be ro- tated in any suitable manner, and from any

suitable source, such for instance, as by a belting over the pulley 19. From the arrangement thus described it will be seen that if the lime cakes within the chambers, and the strain reaches the breaking point upon 70 any of the parts, the chains 12, 13, or 18 being the weakest portion of the machine, will break, thereby shutting down the machine before any internal parts are broken and serious injury done. These chains are com- 75 paratively cheap, easily mended, and can be quickly mended or replaced, and greatly lessens the expense of upkeep, and increases the efficiency of the machine. The chains referred to may be suitably adjusted, or re- 80 placed by the movement of the pulleys or idlers 38, as will be readily understood.

To enable the constant use of concentrated chlorin gas, it is desirable to employ suitable cooling means for the respective tubes. 85 I have shown one simple arrangement wherein I supply suitable water jackets 20 for the tubes, each communicating through a passage 21, at opposite ends, to the tube immediately above and below the same. 90 Water, or other suitable cooling medium is fed into the topmost tube, and is allowed to flow by gravity to the bottom tube, and out therefrom, as will be clearly understood.

To enable an operator to keep close watch 95 of the progress of the lime through the machine, suitable removable doors or windows 22 may be provided throughout the length of the tubes, as shown in Figs. 10 and 12.

In the standard form of Hasenclever ma- 100 chine, great difficulty has been encountered in securing proper feeding of the lime into the machine due to the fact that heretofore it has been the custom to feed the lime directly into the first or top tube. Where the 105 lime comes in bulk, it has a great tendency to accumulate due to the moisture of the atmosphere, or other reasons thereby forming a hard mass. This, of course, subjected the 110 agitator shaft and the agitators of the top tube to considerable strain, and to the possibility of breakage. Further, to prevent choking the machine from an exorbitant feed, it was necessary to provide a hopper with a very restricted opening into the 115 machine, and when lumps or cakes of the lime covered such opening, the feed stopped, thereby necessitating an attendant to agitate the lime in the hopper, and to break up such lumps or cakes. To obviate this difficulty, 120 I provide an auxiliary cylinder or tube 23, opening at one end into the top tube or powder chamber 1, and through which extends a screw shaft 24 provided with screw threads 25, as shown in Figs. 6 and 9. The shaft 24 125 has secured thereto a gear or sprocket wheel 26 which may be rotated in any suitable or desirable manner. I prefer to operate the same by means of a chain or other connection 27 with a similar sprocket 28 mounted 130

on the same agitator shaft 4 as is the wheel 11, hereinbefore described. (See Fig. 1). The hopper 16 opens into the auxiliary feed cylinder 23, and it will be noted that by this 5 arrangement, the screw shaft automatically breaks up the cakes or lumps of lime, insures a steady and equal feed, and automatically stops the feed when the rest of the machine is inoperative.

10 As hereinbefore explained, it is desirable to agitate the lime within the hopper. I have shown one arrangement for accomplishing this wherein I provide the hopper 16 with a loosely fitting funnel 29, see Fig. 15 9, which funnel is provided with a thick or reinforced portion 30 on opposite sides thereof. Suspended from the mouth of the hopper 16 on opposite sides thereof, are two arms or pendulums 31, provided with a 20 heavy hammer 32 secured near the free end thereof. Passing through the wall of the hopper 16, to come in contact with the reinforced portions 30 of the loose fitting funnel 29, are pins 33. It will be seen that when 25 the pendulums 31 are swung, the hammers 32 will come in contact with the pins 33, causing the same to shake or jar the funnel. Any suitable means may be employed to actuate the pendulums 31. I have shown one 30 arrangement wherein I mount shafts 34 in suitable brackets 35 carried by the cylinder casting 23, and driven by suitable gear or friction connection 36, by the screw shaft 24. Mounted on the shafts 34 to rotate there- 35 with are arms 37, which on rotation of the shaft, come in contact with, and swing outward from the hopper, the free ends of the pendulums 31.

As has been hereinbefore explained, it is 40 desirable to provide means for preventing the lime accumulating in the tube at the point immediately below the opening therein from the tube above it. For this purpose I provide a suitable "scraper" 39 mounted 45 on the agitator shaft 4 of each tube, to be rotated thereby and positioned closely adjacent to the closed ends of the tube.

It has heretofore been the practice to collect the product in a receptacle positioned 50 under the discharge orifice of the bottom tube, and then carry away this product to be sifted to secure the commercial form of bleaching powder. I propose to eliminate this extra operation by providing the discharge orifice with a sifting screen so that 55 the commercial product is secured directly from the machine.

In Fig. 5 I have shown one arrangement 60 wherein the tube 1 is open at its end and discharges directly into a screen 40. The fine commercial form of the product is thereby obtained directly from beneath the screen, while the large lumps of the same are discharged from out of the mouth of the same, 65 due to its slanted position as shown.

In Figs. 3 and 4, I have shown a modified arrangement wherein I mount the screen 41 on the shaft 3 of the tube, to be rotated thereby, and the product, being thus sifted through the screen, is collected at the discharge orifice 42 in its fine commercial form, 70 as will be readily understood.

It has heretofore been the practice, by any suitable means, to cause the gas to travel through the machine by suction, and to discharge the gas into atmosphere in the state in which it leaves the machine. In the course of its travel through the various tubes, the gas picks up fine particles of the lime, and at the point of discharge of the 80 gas, this fine powder is likewise discharged, causing great waste, and making it unhealthy and disagreeable to work about the machine at that point. For this and other reasons I provide the discharge pipe 9 with 85 a rectangular portion, as shown in Figs. 7 and 8, and I provide a number of screens 50 in said pipe, adapted to be readily removed to be cleaned or replaced through an opening in said pipe, which opening is provided 90 with a cover 51. The exhaust pipe may be provided with a port or window 53 to allow the same to be cleaned when necessary. Thus it will be seen that the exhaust gas will be thoroughly filtered before being discharged 95 into the atmosphere, thereby saving a waste of the lime and at the same time eliminating the disagreeable result of the fine powder flying around through the air.

While I have shown and described in detail specific arrangements embodying my invention, it will be understood that my broad invention, as defined in the claims, is not to be limited or restricted thereto, as many modifications will readily occur to those 105 skilled in the art without departing from the spirit or scope of my invention.

Therefore, what I claim as new and useful and of my own invention and desire to secure by Letters Patent, is,—

110

1. In a bleaching powder machine, a plurality of tubes arranged the one above the other, and communicating with each other at opposite ends, means for admitting lime into the bottom tubes, means for admitting lime in the top tube, means for causing said lime to travel the length of each of said tubes, in succession in opposition to the direction of travel of said gas, and means located on the bottom tube for sifting said lime at the end of its travel in said tubes.

2. In a bleaching powder machine, a plurality of tubes arranged in sets of three, agitator shaft for each of said tubes, a chains actuated from a common source rotating said agitator shafts of each set.

3. In a bleaching powder machine, a combination of a shaft, agitators arranged therein to rotate therewith, and a sifting screen mounted on said shaft.

120

4. In a bleaching powder machine, the combination of a powder tube, closed at its ends, a shaft located in said tube and passing through the ends thereof, agitators mounted on said shaft, scrapers also mounted on said shaft and positioned immediately adjacent the ends of said tube and within the same, and means for rotating said shaft.
5. In a bleaching powder machine, a plurality of tubes arranged the one above the other and communicating with each other at opposite ends, means for admitting lime in the top tube, means for causing said lime to travel the length of each of said tubes, means for admitting gas into the bottom tubes, means to cause said gas to travel in a direction opposite to the travel of said lime, means for sifting the lime at the end of its travel in said tubes, and means for filtering
6. In a bleaching powder machine, a plurality of tubes arranged the one above the other and communicating with each other at opposite ends, means for admitting lime in the top tube, means for causing said lime to travel the length of each of said tubes, means for admitting gas into the bottom tubes, means to cause said gas to travel in a direction opposite to the travel of said lime, means for sifting the lime at the end of its travel in said tubes, and a removable filtering screen for filtering said gas at the end of its travel in said tubes.
- 10
- 15

said gas at the end of its travel in said tubes.

6. In a bleaching powder machine, a plurality of tubes arranged the one above the other and communicating with each other at opposite ends, means for admitting lime in the top tube, means for causing said lime to travel the length of each of said tubes, means for admitting gas into the bottom tubes, means to cause said gas to travel in a direction opposite to the travel of said lime, means for sifting the lime at the end of its travel in said tubes, and a removable filtering screen for filtering said gas at the end of its travel in said tubes.

In testimony whereof I have hereunto set my hand on this 31st day of December A. D., 1915.

ICHIRO ISHIKAWA.
